UNITED STATES PATENT OFFICE.

ARTHUR C. SOULE, OF SAN FRANCISCO, CALIFORNIA.

WINDOW-MOUNTING.

1,256,839.

Specification of Letters Patent. Patented Feb. 19, 1918.

Application filed November 23, 1914. Serial No. 873,646.

To all whom it may concern:

Be it known that I, ARTHUR C. SOULE, a citizen of the United States, residing in the city and county of San Francisco, State of California, (whose post-office address is 226 Judah street,) have invented new and useful Improvements in Window-Mountings, of which the following is a specification.

10 This invention relates more particularly to the mounting and control of casement windows, in which the sash is mounted on vertical pivots adjacent to one edge thereof, and slidably guided on the sill at the bottom of the casement, and in the overhead lintel at the top; the inner edges of the sash abutting the usual stops in the window framing, to make a weather tight joint around the sash.

20 Among the objects of this invention are to produce a mounting simple in construction, easily installed and adjusted;

That is weather proof; that will not accumulate moisture and snow in its working parts, liable to freeze and interfere with the proper functioning of the various parts;

That is architecturally and commercially attractive; and

That may be installed by the average workman familiar with this class of labor.

Other objects and advantages will appear as the description progresses. In the drawing accompanying and forming part of the present specification, to which like reference characters have been applied, a simple form is shown. I do not wish to be understood as confining this invention to the disclosures made in said drawing and description, as many variations may be introduced, within the spirit of this invention, as defined in the claims succeeding the said description.

In the drawings:

Figure 1 is a perspective view looking toward the pivot edge of a sash having a sash mounting constructed in accordance with this invention, attached thereto. Better to disclose the details and interrelation of the parts, the casement or window framing has been entirely omitted from this view; the mounting being shown in the position assumed when the sash is partly open.

Fig. 2 is a cross section looking down upon the window casement with the sash indicated in full lines, in the closed position.

Fig. 3 is an enlarged side elevation of the

window framing, showing the edge of the sash in full lines in the closed position, and the framing in cross section.

Fig. 4 is a detail in perspective looking down upon the pivotal sleeve and attaching plate attachable to the upper and lower edge of the sash.

Fig. 5 is a similar view of the lower pivot, for engaging said pivotal sleeve, rigidly attached to the slide plate, adapted to engage the guide rail.

Fig. 6 is a similar view of the guide rail or strip adapted to engage the slide plate and showing the adjustment slot to engage the pivotal stud of the control arm.

Fig. 7 is a cross section taken on the line VII—VII Fig. 5, illustrating the upset riser struck up from the body of the guide strip.

Fig. 8 is a similar view of the lower control arm adapted to engage the guide strip and the sash, partly broken away in cross section to disclose the pivotal stud and the manner of attaching it to this control arm.

Fig. 9 is a similar view of the anchor plate for engaging the head of the pivotal stud to hold it in the fixed adjustment beneath the guide rail.

Fig. 10 is a fragmentary detail in longitudinal cross section of the adjusting means for the pivot of the control arm.

In detail the construction, illustrated in the drawings, includes the sash, composed of the top and bottom rails 1 and 2, and the side stiles 3 and 4, glazed in the usual manner.

The window frame or casement includes the usual stool 6 attached to the sill 7, the sides 8 and 9 and the overhead lintel 10, with associated trimming, studding and headers as usual. The sill 7 has the level plane 12 milled therein, corresponding in width to the thickness of the sash above it.

The metal guide rail 13 is fixed on this plane 12, and preferably extends across the width of the window opening. This rail consists of a strip of flat steel of the proper width and preferably having rounded edges. From the body of this rail strip the risers 14 are struck downward, to form the countersunk opening 15 to receive the screws for attaching the rail to the sill. The risers 14 resting upon the surface 12 hold the strip 13 elevated above the surface 12. The pivot 16 is riveted or otherwise rigidly attached to the sliding plates 17 having the inturned edges

18—18. These inturned edges engage the edges of the guide rail 13 upon which the plate 17 slides freely. The lower rail 2 of the sash is bored near its edge to receive the sleeve 19, crimped or otherwise rigidly fixed in the plate 20, secured to the underside of the rail by screws extending through the countersunk holes 21. The edges of the plate 20 are upturned to space the surface of the plate 20 downward, equal to the depth of the groove 22, formed in the rail 2 of the sash, to receive the connecting plate of the control arm, and to keep the nethermost edge of the sash as near to the sill as may be, to contribute to the weatherproofing of the sash at this point when closed. The surface of the plate 20 approximates contact with the surface of the plates 17 when the sash is mounted on the pivot 16, that engages the sleeve 19 embedded in the sash, the swaged shoulder 23 on the rivet engaging the crimped edge of the sleeve 19, resting thereon and supporting the weight of the sash in its pivoted action.

25 The sash is vertically pivoted at the top by the friction shoe 24, engaging the groove 25 in the top lintel of the frame. The friction shoe is mounted on the stem 26, guided in a sleeve embedded in the top rail 1, and crimped in the plate 27, similar to the sleeve and plate construction 19 and 20. The top rail 1 is provided with the groove 28, similar to the groove 22, and performs the same function at the top of the sash. The compression spring 29, confined between the friction shoe 24 and the plate 27, causes the shoe 24 to exert a frictional pressure against the top of the groove 25, in proportion to the tension of the spring 29, the purpose of which will be disclosed later.

30 To maintain the sash perpendicular in its various evolutions it is provided with control arms at the top and bottom. The lower arm 30 is provided with the plate 31, pivoted thereto by the rivet 32, and provided with the screw holes 33 by which it is secured by screws to the lower rail 2, within the groove 22 at the proper distance from the pivotal center 16. This distance will vary with the width of the sash. The inner end of the control arm 30 is provided with a pivotal stud 34, having the enlarged head 35, and fixed in the end of the arm by the reduced stud 36, riveted in the end of the arm 30. 35 Some adjustment is necessary to determine the proper pivotal point for the attachment of the control arm to the window frame; this adjustment is provided for in the guide rail 13. The guide rail is provided with the opening 37 to admit the head 35 of the pivotal stud. The slot 37 starts in this opening and extends backward in the body of the guide strip; the width of this slot admits the diameter of the stud 34. The anchor plate 38 is provided with the opening 39, to re-

ceive the head 35 protruding through the thickness of the guide rail. This plate is provided with the slots 40, to receive the screws extending through the holes 41 in the guide rail. The screws extending through the holes 41 enter the sill 7. Then the control arm 30 and its combinative elements are assembled, with the sash and the guide strip as indicated above, the screws through the holes 41 are driven down sufficiently to exert a holding pressure between the guide rail and the sill, to frictionally hold the anchor plate 38. The sash has now been opened and closed, the closed position causing the arm 30, now lying parallel with the rail 2 of the sash, to force the plate 38, the opening 39 of which engages the head 35, to the proper position for the relative pivotal center of the control arm. The sash is now gently opened sufficiently to permit access to the screws extending through the holes 41, that are now driven down to permanently clamp the anchor plate between the rail 13 and the sill 7; the head 35 of the stud revolves freely in the opening 39 that holds the pivotal center of the stud in the proper fixed position, to control the evolution of the sash. It is obviously expedient to also similarly control the upper edge of the sash. This is accomplished by the control arm 42, pivoted at 43 to the plate 44, screwed to the upper rail 1 in the groove 28, in vertical alinement with the rivet 32 of the lower arm. The offset plate 45 is pivotally riveted at 46 to the inner end of the arm 42. The ends 47 of this plate are slotted and adapted to set within the groove 25, the depth of which is equal to the offset in the plate 45. This plate is secured to the lintel 10, by screws extending through the slotted ends 47 of the plate. These screws are driven into the wood to hold the plate 45 reasonably tight, until gentle opening and closing of the sash determines the proper vertical alinement of the rivet 46 and the stud 34; when this is determined these screws are set tight to maintain this vertical alinement.

105 The sash thus mounted and assembled within the window framing is opened by pushing outward on the side 4; this causes the slide 17 to slide toward the center of the window opening, guided by the strip 13; the friction shoe 24 following in alinement therewith in the overhead slot 25; the friction of the shoe 25 under the influence of the spring 29, exerting a sliding friction, sufficient to hold the sash in the desired open position against wind pressure or other influences tending to slam the sash shut or alter its desired position, except by the intention of the operator, who moves the sash by overcoming the friction of the shoe, the leverage of the sash and its control mechanism being in favor of the operator han- 110 115 120 125 130

dling the sash as described, and against wind pressure that is exerted throughout the area of the sash and substantially equalized from both sides of the operative center 5 of the control arms in their engagement with the sash.

The control mechanisms constructed and applied to the sash as described, compel the sash to maintain a perpendicular position in 10 all of its various evolutions.

While I have described the sash as operating in a vertical position in a horizontal plane, it is obvious that it will operate similarly on the vertical plane with the sash in 15 the horizontal position, or in any plane that it may be desired to operate a sash of this character.

The pivotal latch 48 is mounted adjacent to the edge of the sash stile 4, and adapted 20 to engage a recess plate fixed in the side of the window opening, to lock the sash in the closed position. This latch also provides a natural hold for opening and closing the sash.

25 The various metal parts of the structure are sherardized or otherwise treated to prevent rust or corrosion.

Having thus described this invention what I claim and desire to secure by Letters Patent is:

30 1. The combination with a window frame, of upper and lower guides attached to the lintel and sill respectively, a sash, a shoe pivotally engaging the lower edge of said sash contiguous to the corner thereof and 35 slidably engaging the lower guide, a shoe yieldably mounted in the upper edge of the sash in alinement with the first mentioned shoe and slidably engaging the upper guide, 40 and control arms each pivoted at one end to said sash and having its other end adjustably anchored to the frame.

45 2. In combination with a window frame, a guide strip fixed on said frame; a pivot slidable on said strip; a sash mounted on said pivot, and slidably guided in said frame; a control arm pivoted on said sash; a pivotal stud fixed in said control arm, and 50 slidably engaging a slot in said strip; and a lock plate engaging said stud and adapted to be clamped between said strip and the window frame.

55 3. In combination with a window frame; a window sash slidably pivoted in said frame; a control arm pivoted on said sash and having a pivotal stud; a strip fixed on said frame and having a slot engaging said stud; a stop plate clamped between said strip and the frame, and engaging said stud.

60 4. An adjustable pivot for the control

arms of slidably pivoted window sashes, including a pivotal stud fixed on said control arm and having an enlarged head; a strip attachable to the window frame and having an opening therethrough to pass the enlarged head, and a slot leading therefrom engaging said stud between the enlarged head and the control arm; and an anchor plate having an opening therein engaging said enlarged head and clamped between said strip and the window frame. 65

5. An adjustable pivot for the control arms of slidably pivoted window sashes, including a pivotal stud fixed on said control arms and having an enlarged head; a strip 75 spaced above the sill of said frame, on risers formed thereon, and having an opening therethrough to pass the enlarged head, and a slot leading therefrom engaging said stud between the enlarged head and the control 80 arm; and an anchor plate having an opening therein engaging said enlarged head and clamped between said strip and the window frame.

6. The combination with a window frame, 85 of a guide strip attached to the sill thereof and provided with depending portions forming risers to space the strip from the surface of the sill, a sash, a shoe, said shoe slidably engaging said strip and having flanges 90 extending beneath said strip into the space provided by said risers, and means for supporting the upper edge of said sash.

7. The combination with a window frame, 95 of a guide strip having countersunk openings, and depending bosses coinciding with said openings, said bosses serving as risers to space the strip from the surface of the sill, a sash, a shoe, said shoe slidably engaging said strip and having flanges extending beneath said strip into the space provided by said risers, and means for supporting the upper edge of said sash and said frame. 100

8. The combination with a window frame, 105 of a window sash, a pivot attached to said sash and slidably connected with the frame, a control arm having one end movably connected with the sash, the other end having means for engaging the window frame, an adjustable anchor plate coöperating with 110 said arm, and means immovably holding said anchor plate in adjusted position on the sill.

In testimony whereof, I have hereunto set my hand this 14th day of November 1914. 115

AETHUR C. SOULE.
